DRIVE UNIT FOR A BARBEQUE
ROTISSERIE SPITWilliam E. Bartasevich, Glenshaw, Pa., assignor to
Disston, Inc., Pittsburgh, Pa.

Filed May 5, 1972, Ser. No. 250,845

Term of patent 14 years

Int. Cl. D7—02

U.S. Cl. D7—129

FIG. 1

FIG. 2

FIG. 3

FIG. 4

FIG. 1 is a front elevational view of a drive unit for a barbecue rotisserie spit showing my new design.

FIG. 2 is a rear elevational view thereof.

FIG. 3 is a top plan view, the bottom plan view being a mirror image thereof.

FIG. 4 is a right side elevational view thereof, the left side view being a mirror image thereof.

I claim:

The ornamental design for a drive unit for a barbecue rotisserie spit, substantially as shown and described.
